UNITED STATES PATENT OFFICE.

JOHN ROLSTON, OF MINNEAPOLIS, MINNESOTA, ASSIGNEE TO EDWARD F. BOUSFIELD,
OF MINNEAPOLIS, MINNESOTA.

LOCK-FORMING DEVICE FOR WIRE HOOPS.

954,886.

Specification of Letters Patent. Patented Apr. 12, 1910.

Application filed September 22, 1909. Serial No. 519,040.

To all whom it may concern:

Be it known that I, JOHN ROLSTON, of 5
Minneapolis, Hennepin county, Minnesota,
have invented certain new and useful Im-
5 provements in Lock-Forming Devices for
Wire Hoops, of which the following is a
specification.

10 My invention relates to tools for tightening
and locking wire hoops on pails or simi-
lar articles and the object of the invention is
to provide a simple, durable tool by means
of which the tightening and locking opera-
15 tion can be quickly and easily performed.

15 The invention consists generally in various
constructions and combinations, all as herein-
after described and pointed out in the claims.

20 In the accompanying drawings forming a
part of this specification, Figure 1 is a view
illustrating the tool in use preparatory to
bending ends of the hoop. Fig. 2 is a simi-
25 lar view illustrating the severing portion
and the manner of bending the hoop ends,
Fig. 3 is a side view of the tool, illustrating
its open position, Fig. 4 is a top view of the
same, Fig. 5 is a sectional view of the line
25 X—X of Fig. 3, Fig. 6 illustrates the twisted
interlocked ends of the hoop showing the
bent portions which are driven into the
stave.

30 In the drawing, 2 represents a portion of
a pail, 3 the wire from which the hoop is
formed. The tool consists of blocks 4 and
5, the former having a shank 6 which is slid-
able within a socket 7 in the latter. A lever
35 8 is pivoted on the block 4 on one side thereof
and an arm 9 is pivoted at 10 on the block 4
and has an inclined slot 11 therein, in which
a pin 12, mounted on the lever 8, is adapted
to slide. A severing knife 13 is carried by
40 the arm 9 and is adapted to drop into a re-
cess 14 in the upper edge of said arm when it
is elevated. The severing knife has a be-
velled lower end 15, one edge of which co-
operates with a fixed cutter 16 on the block
45 4, the wire from the reel being supported on
the cutter 16 and severed between it and the
descending knife 13. A hand grip 17 is
mounted on the block 4 in position to be
grasped by the operator when the lever 8
50 is raised to a vertical position. By means of
this hand grip the operator can hold the
tool stationary during the operation of
bending one end of the hoop. The block

5 is provided with a lever 18 pivoted at 19
and carrying a plate 20 that is adapted to 55
slide vertically on a flange 21, which pro-
jects from one side of the block 5. The
blocks are provided with stationary jaws 22
and 23, having inclined slots 24 and 25 there-
in, which are adapted to receive the wire 60
hoop, the flange 21 projecting into the path
of the end of the hoop and acting as a stop
therefor. The stationary jaws are spaced
suitably from the flange 21 and from the
cutter 16 and in these spaces the severing 65
knife 13 and the plate 20 are vertically mov-
able when the levers are operated. The sev-
ering knife will first cut the wire and its
beveled end bearing on the hoop will force
70 down the extreme end of the hoop until it is
at right angles to the main portion thereof.
A corresponding bend will be formed at the
other end of the hoop by the descent of the
plate 20.

75 The lever 8 has a lug 26 thereon, pivotally
connected by a link 27 with the block 5 and
the eccentric connection of the lever 8 with
the opposite block will cause a separation
80 of the blocks when the said lever is swung
down to a horizontal position. The separa-
tion of the blocks takes place when the
initial bends have been formed in the ends
85 of the hoop after the wire is severed and
the effect of said separation is to draw the
wire snugly into the annular groove in the
surface of the pail or other article to be
hooped. When the ends of the hoop are
90 bent and the wire placed under tension, the
tool is then turned a half revolution, twist-
ing the crossed ends of the wire upon one
another, as shown in Fig. 6. The hoop will
then be locked securely on the pail and when
95 the tool is removed the bent ends may be
driven into the stave, thereby completing
the hooping operation and presenting a neat,
finished appearance to the pail or other
package. It will be noted in this case that
100 the jaws in which the wire is inserted are
stationary and the wire is held therein by
bending its ends and tension is obtained on
the hoop by the separation of the blocks in
which the jaws are mounted.

I claim as my invention:

1. A device of the class described, com-
prising relatively movable blocks having 105
slots therein adapted to receive a wire hoop,

the ends of the hoop projecting beyond said slots, and means for bending the projecting ends of the hoop and separating said blocks to put the hoop under tension, substantially 5 as described.

2. A device of the class described comprising two blocks, one having a shank slideable within a socket in the other, stationary jaws mounted on said blocks and having 10 slots therein to receive a wire, the wire projecting through said slots and beyond said jaws and means for bending the projecting ends of the wire and separating said jaws to put the wire under tension.

3. A device of the class described comprising blocks, stationary jaws mounted therein and having slots adapted to receive a wire hoop, the wire extending through said slots beyond said jaws, means mounted 20 on said jaws for severing the wire and bending the extended ends of the hoop to lock it in said jaws, and levers mounted on said blocks and arranged to operate said bending and severing means, substantially as described.

4. A device of the class described, comprising relatively movable blocks, jaws thereon having slots to receive a wire hoop, the ends of the hoop projecting beyond said 30 slots, means arranged to sever the wire and to bend the ends of the hoop, levers operatively connected with said means, and means provided in connection with one of said levers for separating said blocks when said 35 lever is operated, for the purpose specified.

5. A device of the class described, comprising blocks, jaws mounted thereon and having slots to receive a wire hoop, levers pivoted on said blocks, a stationary cutter 40 carried by one of said blocks, a severing knife operated between said cutter and the stationary jaw of that block, and a pivoted arm supporting said severing knife and hav-

ing a sliding connection with one of said levers.

45

6. A device of the class described, comprising blocks, one having a shank to enter a socket in the other and slide therein, stationary jaws carried by said blocks and having slots to receive a wire hoop, wire severing and bending means arranged to engage and bend the ends of the hoop against the surfaces of said jaws, and levers pivoted on said blocks respectively and operatively connected with said severing and bending 50 means, the lever of one block having an eccentric connection with the other block, whereby at a predetermined point in the movement of the lever said blocks will be separated and the wire put under tension. 55

7. A device of the class described, comprising relatively movable blocks having slotted jaws adapted to receive the ends of a hoop, means for bending the ends of the hoop in said jaws, levers pivoted on said 60 blocks respectively, the lever of one block having an eccentric connection with the other block, whereby at a predetermined point in the movement of said lever said blocks will be separated and the hoop put 65 under tension.

8. A device of the class described, comprising blocks, slotted jaws carried thereby and adapted to receive a wire hoop, means for bending the ends of the wire, and a lever 70 mounted on one block and having an eccentric connection with the other block, whereby at a predetermined point in the movement of the lever said blocks will be separated to put the hoop under tension. 75

In witness whereof, I have hereunto set my hand this 14th day of September 1909.

JOHN ROLSTON.
